PLEURAL DIAGNOSIS AND TREATMENT

John L. Bloomheart, Toledo, Ohio, assignor to
Martha F. McKesson, Toledo, Ohio

Application November 29, 1937, Serial No. 177,001

2 Claims. (Cl. 128—184)

This invention relates to handling gas to and from a patient, especially apart from normal respiration.

This invention has utility in establishing a duct, passage or way into the thorax, exterior of the lung-encompassing envelope, and there establishing a chamber to be definitely controlled as to capacity in the introduction of gas, as air, for effecting collapsing of a lung portion or portions. 10 This control is even to the extent of plus or minus gas flow for removing from as well as delivering fluid or gas to this chamber for definite control thereof as to capacity and pressure therein.

Referring to the drawings:

15 Fig. 1 is a front elevation of the cabinet, open, and with parts broken away, as extending to a patient to be treated;

Fig. 2 is a view looking into the back of the casing or cabinet of Fig. 1, parts being broken away;

20 Fig. 3 is a section through the cabinet on the line III—III, Fig. 2, looking in the direction of the arrow at the liquid or water pressure manometer;

25 Fig. 4 is a section on the line IV—IV, Fig. 2, looking in the direction of the arrow at the mercury or gas volume manometer;

Fig. 5 is a diagrammatic view of the duct system in the device;

30 Fig. 6 is a section on the line VI—VI, Fig. 2, looking down on the reservoir or main chamber and manometers; and

35 Fig. 7 is a partial diagram of the system of Fig. 5, adapted for minus instead of plus operation with the patient, and accordingly effective to exhaust or remove air from the cavity as about the lung envelope.

Bosses 1 of rubber may provide a soft support for casing having bottom 2, sides 3, 4, rising therefrom to top 5 as a rectangular or oblong frame. Holes 6 (Fig. 2) in the back of this frame 40 may receive screws 7 in mounting back panel 8 to close the rear of this casing or cabinet. The side 4 carries hinge sections 9 with eye adapted to receive hinge section pins 10 fixed with panel 11 (Fig. 1) as a cover equipped with boss portions 12 in registry with boss portions 13 on the side 3, which portions 13 have hinge bails 14 to swing over the boss portions 12 in detachably holding the cover panel 11 in closed position. Arch brackets 15 on top side 5 mount links 16 for 45 swingably carrying handle 17, and thereby completing a portable housing for this pneumothorax device as a self-contained unit.

Bolts 18 (Fig. 4) mount brackets 19 carrying 50 bolts 20 assembling intermediate partition or dia-

phragm 21 between the side walls 3, 4, in the rectangular frame of the casing. This partition 21 has medial concavity 22 in which is located reservoir or chamber 23 as held by straps 24 (Fig. 2) anchored by bolts 25 with this partition 21. This chamber 23 rests on the bottom 2 at one side thereof. Anchored by bolt 26 with the bottom 2 is U-block 27 engaging duct 28 between mercury chamber 29 on one side of the partition 21 and minor foot chamber 30 on the other side thereof, from which rises mercury manometer tube 31 connected by block 32 having fiber filling 33 to port 34 to the atmosphere. The mercury chamber 29 has connection by duct 35 to fitting 36 with the chamber 23, thereby providing direct connection for disclosing pressure or volume condition in such chamber.

On the opposite side of this chamber 23 is fitting 37 controlled by valve 38 for opening and shutting communication between duct 39 and this chamber 23. This duct 39 extends to fitting 40 through the partition 21 and may there have slip communication with duct 41 past check valve 42 (Figs. 1, 3, 5) to compressible rubber bulb or pump 43. In compressing this bulb 43 it may act 25 as a pump in drawing air past entrance check valve 44 at nipple 45 and expelling such air past the check valve 42 for flow by the duct 41 in the chamber or reservoir 23 and thereby build up pressure in the mercury manometer. 30

On this partition 21, adjacent the riser duct 31 of the mercury manometer, are graduations 46, herein shown in cubic centimeters to indicate the volume of gas as air pumped into this chamber 23 on the basis of atmospheric pressure. For 35 the purposes of this device, the zero on this scale is at the charged pressure for this reservoir or chamber 23, and as such pressure drops from the zero it indicates the amount of gas at atmospheric pressure delivered from this chamber 23. 40

The chamber 23 has at its top three-way valve fitting 47 operable by hand wheel 48 on the side of the partition away from the chamber 23 and on the side which exposes the bulb pump 43. To this fitting 47 is connection by duct 49 (Figs. 2, 5) 45 from liquid manometer tube 50, which extends on the side of the partition 21 upon which is located the chamber 23 down to base fitting 51 connected by duct 52 (Fig. 3) as held by U-block 53 and bolts 54 at the bottom 2. This duct 52 is in communication with companion base fitting 55 on the opposite side of the partition 21 from the duct 50 and base fitting 51. At such position forward of the partition 21, this base fitting 55 carries riser manometer tube 56 parallel to the mercury man- 50

ometer tube 31 on the opposite side of medial convex portion 57 of this partition 21 (Fig. 1). This manometer tube 56 at its upper portion carries block 58 with cut-off valve 59 adjacent port 60 in the upper wall 5 (Figs. 1, 3).

Mounted on the inside of the door panel 11 by screws 61 is helical spring 62 as a holder for desired appurtenances in connection with this apparatus. In this holder is slender rod 63 having eye or handle 64. Upon opening the valve 59, in the event the colored water or liquid in the tube 56 has air bubbles therein, insertion of this rod 63 through the opening at the cut-off valve 59 will serve to clear the air and thus allow the gage 15 liquid to form as a body from the base fitting 55 in its rise along graduation plate 65 having elongated slots 66 engaged by screws 67 extending through the partition 21 and carrying thereon springs 68 as compressed by nuts 69. There is, 20 accordingly, a frictional holding of this gage strip 65 permitting shifting of such to bring the zero point on this gage strip with its pointer 70 at the atmospheric liquid level in this gage tube 56. There is thus ready adjustment for evaporation 25 or other loss of this liquid. In practice, when the apparatus is out of use, the valve 59 may be closed to minimize the evaporation loss.

Pointer 71 at the hand wheel 48, when at "off" position, shuts off communication between the 30 reservoir 23 and the duct 49 to the manometer. In shifting this pointer from "off" position 72 to "pleural pressure" position 73, the duct 49 to the manometer is connected to duct 74 extending back of the partition 21 to fitting 75 as through 35 the partition, with which fitting 75 there is slip-fit of duct 76 having therein filter 77, say of impregnated fiber as cotton, thence by duct section 78 to fitting 79 carrying tubular needle 80 adapted for insertion in patient 81, say into the 40 thorax to an extent to enter about or outside the envelope for the lung but interior of the chest cavity. The readily collapsing condition of the lung tissue as exposed to atmospheric pressure exterior of the lung cavity or envelope tends to collapse. This exposure to the needle with 45 communication to the pressure or liquid manometer may disclose the condition of such cavity whether in diagnosis under disease and filled with any accumulation of respiration-interfering liquid 50 or gas as a matter of diagnosis.

In treatment, this degree of pressure condition may be determined. For instance, should the investigation reveal a disturbed or diseased condition, say local to certain portions of the 55 lung, the collapse may be effected by allowing gas as air to enter through this tube 78 and needle 80 to a desired degree of collapse, which as maintained for a period provides a period of rest for such tissue with improved chance for recovery; 60 and as such rest period is determined of sufficient extent the collapse condition may be removed. In practice, it is not usual to maintain the needle communication but effect such intermittently in checking the condition of the patient. In this connecting up as herein, the condition has been for ascertaining the pleural pressure 65 at the point 73 for the hand wheel 48.

With the condition that it may be desired to introduce pressure or gas into this cavity exterior of the lung envelope as having access thereto by the needle 80, the attending physician may operate the hand wheel 48 to shift the pointer away from the "pleural pressure" indication 73, past the "off" position 72, to graduations 82; 75 "1" being to the slightly open, "2" and "3" to

the more open, and "4" to the fully open position, for communication of this needle 80 as on tube or duct 78, past this three-way valve to be connected by the fitting 47 with duct 83 to the reservoir or chamber 23. This allows the 5 pressure air in this chamber to flow at a desired or elected rate for entrance into this cavity about the lung envelope to effect collapsing of the lung. This flow of air from this chamber 23 reacts for 10 volume on the position of the column of mercury in the manometer tube 31, and such is disclosed by the graduations 46. The cubic centimeter extent of this flow is definitely determined. As such extent of collapse is effected, the hand wheel 48 may be operated to shut off 15 this gas supply by bringing the pointer 71 to "off" position 72. It is to be noted that this hand wheel is a single means for operation which will connect up the needle 80 for pressure disclosure as to the manometer, the liquid manometer 20 scale 65, or independently thereof a flow of gas to the patient for disclosing such flow on the graduations 46 at the mercury manometer 31. This precludes an alternative operation or gas pressure flow into the liquid manometer tube 56. 25

In the event the pleural pressure after the treatment be excessive in the patient or there be purpose to exhaust such cavity, the duct 76, instead of being connected at fitting 75, is connected at nipple 45 adjacent the bulb or pump 30 43 and outside the intake check valve 44. As thus connected up, operation of the pump 43 effects exhausting in the duct 78 and accordingly withdrawal of liquid or gas by way of the tubular needle 80 from the patient, and this may be to a measure or extent desired, for in this operation the hand wheel 48 may have its pointer 71 to communicate with the graduation 72 and flow past "on" valve 38 into the chamber 23. Should there be purpose in determining the drop 35 in pressure effected in this cavity, the hand wheel 48 is adjusted to have its pointer 71 at "pleural pressure" point position 73, thereby enabling the attending physician to take the reading on the graduation 65 at a sub-atmospheric pressure, that is, below the point 10 or above. 40

With this set-up of equipment, the tubing may be left connected with the fittings or merely hung in the cabinet, say about the mounting for the hand wheel 48. It is well in handling to have 50 the valve 59 closed as well as the valve 38 at "off" position and likewise the valve wheel 48. This device in its set-up is compact, with range of operation for gas delivery to or from a patient, and especially adaptable in pulmonary 55 cases, with ready adaptability for control in diagnosis as well as for maintenance of a treatment condition during an interval as desired for lung rest and extent found acceptable therefor.

What is claimed and it is desired to secure by 60 Letters Patent is:

1. Pneumothorax apparatus embodying a mercury manometer graduated for gas volume, a liquid manometer graduated for gas pressure, said manometers each having upward from the graduations thereon an atmospheric pressure responsive port open in normal operation hereunder, a reservoir, independent ducts from the reservoir to the manometers, the duct to the mercury manometer being from the top of the reservoir, valve means in the duct between the liquid manometer and the reservoir, a tube adapted for communication with the reservoir, a needle connected to the tube and insertable in the patient to be treated, a bulb pump having assem- 75

bly means adapted selectively to connect the pump to charge the reservoir for gas flow to or from the patient, each of said manometers having its atmospheric opening independent of said 5 valve means, tube and pump, and a casing from which the tube extends to the needle and in which casing the apparatus is housed with the manometers disposed parallel to each other, said casing having a cover section at closed position to house the pump and duct with the needle terminus.

2. Pneumothorax apparatus embodying a mercury manometer graduated for gas volume, a liquid manometer graduated for gas pressure, 10 said manometers each having an atmospheric pressure responsive port open in normal operation hereunder, a reservoir therebetween, valve means between the latter manometer and the reservoir, a tube adapted for communication with 15 the reservoir, a needle connected to the tube and insertable in the patient to be treated, a bulb pump having assembly means adapted selective-

ly to connect the pump to charge the reservoir for gas flow to or from the patient, each of said manometers having its atmospheric opening independent of said valve means, tube and pump, a casing from which the tube extends to the 5 needle and in which casing the apparatus is housed with the manometers disposed parallel to each other, said casing having a cover section at closed position to house the pump and duct with the needle terminus, said tube from the 10 needle at one position of the valve means being in communication with one of said manometers, at a second position of the valve means being entirely disconnected from gas flow relatively thereto, and at a third adjusted position 15 of the valve means adapted to connect the reservoir for selected rate of flow of gas to the needle, said valve means in said operation providing a control precluding gas flow into the liquid manometer.

JOHN L. BLOOMHEART.
